UNITED STATES PATENT OFFICE.

EDWARD B. TYLER, OF WAYNE CITY, ILLINOIS.

CONCRETE-POST MOLD.

1,417,644.

Specification of Letters Patent. Patented May 30, 1922.

Application filed June 24, 1920. Serial No. 391,393.

To all whom it may concern:

Be it known that I, EDWARD B. TYLER, citizen of the United States, residing at Wayne City, in the county of Wayne

5 State of Illinois, have invented certain new and useful Improvements in Concrete-Post Molds, of which the following is a specification.

This invention relates to new and useful 10 improvements in molds for cement posts; the primary object of the invention being to provide a device of this nature which may be easily and readily removed from the post shortly after the same has been poured so 15 that the mold may be immediately used for the formation of other posts; thereby obviating the loss of time which results from the use of ordinary molds wherein it is necessary to permit the mold to remain around 20 the post until the same has been set and hardened.

Another object of the invention is to provide the device of the above nature which embodies a construction rendering it possible 25 to remove the mold from the post as set forth above and without the necessity of lifting or moving the post from the position in which it was poured.

Another object of the invention is to provide 30 the edges of the mold with reinforcing straps or irons which besides performing their well known functions also provide relatively broad top and bottom edges for the mold whereby a trowel or shovel may 35 be engaged therewith and may be moved therealong to finish the post, the reinforcing straps also serving to properly support the mold and to provide a novel mounting for a latch.

40 A still further object of the invention is to provide the mold with openings through which may be inserted fence wire hole forming elements so that the post will be finished with the openings therein.

45 Still another object of the invention is to provide an improved method of forming fence wire openings in a post and for engaging reinforcing elements in the post.

Other objects and advantages of the invention 50 will become apparent during the course of the following description.

In the accompanying drawings forming a part of the application and wherein like numerals are employed to designate like parts 55 throughout the several views—

Figure 1 is a top plan of the invention.

Figure 2 is a side elevation of the same.

Figure 3 is an enlarged fragmentary side elevation of the mold illustrating the locking means therefor.

60

Figure 4 is a section taken on the line 4—4 of Figure 3.

Figure 5 is a transverse section through the mold and cement post therein.

Figure 6 is an enlarged fragmentary longitudinal section of one end of the mold taken on the line 6—6 of Figure 2, and,

Figure 7 are views of wire fence hole forming elements.

Referring to the drawings wherein for 70 the purpose of illustration is shown the preferred embodiment of my invention, the numeral 8 designates my improved mold in its entirety, and by viewing Figures 1 and 5 it will be apparent that the mold is provided with an open top and bottom so that the mold may be removed from the newly formed post shortly after it has been poured, tamped and finished, without it being necessary for the operator to lift or convey the 80 post from the time it is poured until the time it is set and completed.

The mold consists of a pair of side walls 9 and 10 and a pair of end walls 11 and 12. These walls may be constructed from any 85

kind of desired material, but the body portions thereof, I preferably construct from wood to insure the mold of lightness so that it may be readily and easily conveyed from one place to another. Each longitudinal edge of the side walls has secured thereto a T-angle iron or strap 13 which extends longitudinally of the side to reinforce the same as well as to properly support the mold and to form connections between the 95

walls of the same. One half of the horizontal arm of the T-arm is secured to the longitudinal edge of its respective side wall in a manner to dispose the vertical arm 14 of the T-arm in engagement with the outer 100

face of its respective side so that it may be secured thereto by fastening elements 15. As will be seen, the side walls gradually converge toward one end so as to provide a mold which will form an upwardly tapering post.

The top and bottom edges of the end walls 11 each have secured thereto, a reinforcing strap 16, the ends of each being extended beyond the ends of the end wall as 110

clearly seen in Fig. 6. The relative inner edges of these straps 16 as well as the inner

ends 17 of the horizontal arm of the T-irons 13 are flush with the inner surfaces of the mold walls, while the outer edges of these straps and T-irons extend well beyond the 5 outer surfaces of the walls to facilitate connecting the walls to one another. A pair of bars or straps 18 are fastened to the inner faces of the outwardly extending portions of the T-irons and are connected to corresponding extending ends of the straps 16 by means of bolts 20. The ends 19 of the straps 16 are provided with a plurality of apertures 21 so that when it is desired to make the base of the concrete post wider, 10 the bolts 20 may be removed and associated with the outermost openings 21 in the straps 16.

Referring to Figures 1 and 6, it will be seen that the opposite corresponding ends 20 of the straps 16 are cut away as shown by the numeral 22 so that the arcuated extended ends 23 of the T-irons 13 of the side wall 10 may be pivotally connected by bolts 24 to straps 25 secured to the extended portions 25 of the straps 16, thereby facilitating the inner end surface of the wall being disposed flush with the outer end of the wall 11 when the mold is in position to retain the concrete.

The opposite end 12 of the mold has secured to its top and bottom edges a pair of straps 26 which are extended beyond the ends of the body portion of the end 12. The straps 26 are cut away at one end in a manner identical with the straps of the opposite end and are pivotally connected to the T-irons 13 of the side wall 9 by bolts 27. The opposite ends of these straps 26 are provided with a plurality of apertures 28 for cooperation with a latch which will be 30 presently described. As clearly shown in Figures 1 and 4, ornamental elements 29, in the present instance being a pair of arcuated plates are secured adjacent the upper ends of the two side walls and their free 35 edges abut with the bottom of the end 12 so that the top of the post formed by the mold will have a pair of its upper edges rounded.

Referring more particularly to Figures 3 and 4, it will be noted that one end of the side wall 10 is extended beyond the T-irons 13 to about with the free end of the end wall 12. The vertical arm 14 of the T-iron 13 associated with the opposite edges of the side wall 10 are extended with the side wall 55 and rolled back upon themselves to form bearings 30 which receive the free oppositely directed ends of a resilient latch loop 31. The inner edges 32 of these rolled portions or bearings converge outwardly of the side wall to form the rolled portions into cam bearings so that when the resilient latch loop is swung outwardly of the side wall, the arms of the loop will engage the cam surfaces and cause the free ends of the 60 loop to move inwardly so that they will be

out of engagement with the apertures 28 in the end wall 12. It will be seen that the side walls 10 may swing outwardly of the mold when the latch loop is disposed in close proximity with the side wall. Likewise the 70 end 12 may swing outwardly of the mold whereby the latter may be removed from the concrete post. However, when it is desired to lock the sides and ends in position to receive concrete for another post, the end 75 12 is first swung inwardly into which the side wall 10 is moved so that its extended end enters between the straps 26 and abuts with the free end of the end wall 12. This 80 loop is then swung to be arranged in close proximity with the side of its associated wall which permits the free ends of the loop to move outwardly of each other and through aligned apertures 28 in the straps 26. This 85 of course locks the walls of the mold together so that there is absolutely no possibility of the concrete forcing the walls apart.

In order that fence wire openings may be provided in the posts formed by the mold, each side wall is provided with a 90 plurality of aligned apertures through which are passed a plurality of hole forming devices 34 as shown in Figure 7. These elements are passed through the aligning openings 33 in the two side walls before the 95 concrete is poured into the mold and after the same has been completely filled, and finished the elements 34 may be removed leaving a transverse opening through the 100 concrete mold.

When it is desired to finish the concrete post openings with linings, the mold is filled up to the lower edges of the openings 33 with concrete. After this has been done a plurality of sleeves are interposed between the 105 sides of the mold so that their openings align with those disposed in the sides of the mold. Pins 36 or other suitable means are then passed through the openings in the sides of the mold which align and also through the 110 sleeves 35 whereby they are maintained in correct position in the center of the post being formed. More concrete is then poured into the mold after which it is tamped to pack the same around the sleeve and after the mold has been completely finished the pins 36 are removed and the sleeves 35 are left imbedded in the concrete post. Therefore, it will be apparent that besides forming 115 linings for the openings, the sleeves also reinforce the concrete post to a certain extent.

The foregoing description and the accompanying drawings have reference to the preferred or approved embodiment of my invention. It is to be understood however that 125 such changes may be made in construction and arrangement of parts, materials, dimensions, etc., as may prove expedient and fall within the scope of the appended claims.

Having thus fully described my invention 130

what I claim as new and desire to secure by Letters Patent is:—

1. A post mold including side and end walls, one end wall having its opposite sides 5 extended and provided with apertures, a resilient latch carried by one side wall for cooperation with said apertures, and cam means cooperating with the latch for causing the same to move to disengage and engage said apertures.
2. A post mold including side and end walls, one end wall having apertures therein, reinforcing straps extending along the edges of one side wall, the corresponding ends of 15 the strap being formed into cam bearings, and a resilient latch having its free ends received in said bearings for cooperation with the apertures in the end wall.
3. In a post mold including a plurality of 20 walls, one end wall being pivotally connected to one side wall, and ornamental elements secured to the side walls and adapted for engagement with the end wall when the walls are in cooperative relation.
- 25 4. A post mold including sides and ends, pivotal connections between the sides and ends at a pair of diagonally arranged cor-

ners of the mold, and adjustable connections between the other corners of the mold whereby the size of the same may be varied at will. 30

5. A post mold including side and end walls, one end wall having a plurality of apertures therein, cam bearings on one side wall, and a resilient latch having its free ends received in said bearings for cooperation 35 with the apertures in the end wall whereby the free ends of the latch will be operated by the cam bearings upon movement of the latch.

6. A mold comprising a pair of spaced side 40 walls having alining apertures therein, a sleeve adapted to be positioned between the side walls with its opening alining with the alined apertures in the side walls, and its means extending through the apertures in 45 the side walls and the opening in the sleeve for retaining the latter in position with respect to the mold.

In testimony whereof I affix my signature in presence of two witnesses.

EDWARD B. TYLER.
